UNITED STATES PATENT OFFICE.

LUDWIG T. KUEHL, OF BENTON HARBOR, MICHIGAN, ASSIGNOR, BY MESNE ASSIGNMENTS, TO BAKER-VAWTER COMPANY, OF BENTON HARBOR, MICHIGAN, A CORPORATION OF MICHIGAN.

FILING-CABINET.

1,304,991.

Specification of Letters Patent. Patented May 27, 1919.

Application filed November 2, 1914. Serial No. 869,941.

To all whom it may concern:

Be it known that I, LUDWIG T. KUEHL, a citizen of the United States, residing at Benton Harbor, in the county of Berrien and 5 State of Michigan, have invented certain new and useful Improvements in Filing-Cabinets, of which the following is a specification.

My invention relates more particularly to 10 card cabinets, though as will be apparent, it is in some of its features applicable to other forms of cabinet as well. The purpose of the invention is to provide a cabinet of this character in which the drawer may be readily 15 drawn out to its full extent without danger of dropping from the cabinet or holder and yet may be readily entirely removed when desired, there being a stop so arranged in connection with the drawer and case that 20 the insertion of the drawer puts it into operative position and yet it may be readily withdrawn from operative position by the fingers when the drawer is to be entirely withdrawn.

25 A further object of the invention is to provide means whereby the slides upon which the drawer is mounted are fully withdrawn from the casing with the drawer before the drawer moves with relation thereto, 30 in order to avoid binding. Other features of the invention will appear in connection with the following specification and claims.

In the drawings I have shown and in the specification described in detail a preferred 35 form of my invention as applied to a metallic cabinet but it is to be understood that my invention is not to be limited by the specific disclosure but is set out in the following claims in which I have endeavored to distinguish it from the prior art so far as known to me without, however, relinquishing or abandoning any feature thereof.

In the accompanying drawings Figure 1 is a vertical longitudinal section of a drawer 45 and case embodying my invention on the line 1—1 of Fig. 3; Fig. 2 is a vertical longitudinal section of the same upon the line 2—2 of Fig. 3; the drawer, however, being shown extended and the case broken away; Fig. 3 50 is a horizontal plan through the line 3—3 of Fig. 1; Fig. 4 is a transverse section partly broken away upon the line 4—4 of Fig. 1; Fig. 5 is a detail in side elevation of one of the slides upon which the drawer is mounted

showing also the guide in which the slide 55 works, and Fig. 6 a fragmentary horizontal section on the line 6—6 of Fig. 4.

Each part is designated by the same reference character wherever it appears in the 60 several views.

The casing 7 may be of any suitable form or material but is here shown as generally rectangular and struck up out of sheet metal, the corners being rounded as shown. An entrance for the drawer is formed in the 65 front end by cutting an opening of suitable shape therein and bending back the edges of the metal as at 8 to form an inwardly extending flange. The guides 9 for the slides 10 upon which the drawer is mounted are 70 supported from the side walls by brackets 11 brazed or otherwise secured to said walls, and at their rear ends to the rear wall 12 of the case by angular brackets 13 which are brazed or otherwise secured to the casing 75 and the guides. These guides extend parallel to the top and bottom of the case and are preferably formed of sheet metal having their opposite longitudinal edges 14, 15 80 turned over and toward each other. The 80 slides 16 are also formed of sheet metal and have their opposite edges turned over as at 17 so that the slides are strengthened by said flanges and made to fit snugly within the 85 grooves formed by the overturned edges of the guides. One edge of each guide, as shown the upper edge, is cut away as at 18 to form a shoulder at 19 and the corresponding turned over edge or flange 17 of the slide is cut out as at 20 to form an inwardly extending tongue 21 which when the slide is 90 fully drawn out engages the shoulder 19. In this manner is formed a pair of opposing 95 stops which permit the slide to be drawn outward as far as is desirable and then prevents its further movement. Preferably the movement so permitted is about one-half the length of the slide.

The drawer is likewise preferably formed 100 of sheet metal and its sides corrugated at 22, 23 for the purpose of lending additional rigidity to the structure and in the case of the latter corrugation to provide outwardly extending projections to which the drawer slides 24 may be riveted or otherwise attached. It will be understood that these drawer slides are also of sheet metal but with unturned edges which are received

within the grooves formed by the overlapping edges 17 of the intermediate slides. In order that the intermediate slides 16 may be drawn out to the fullest extent or in other words until arrested by the stops before the drawer moves relative thereto, springs 25 are attached by rivets or otherwise along the inner walls and within the grooves 23 of the drawer but opposite the openings 26, 10 formed in the drawer walls and drawer slides respectively are outwardly bulged or curved as at 28 to project into the openings in the drawer wall and also into the openings 27 in the intermediate slide when the 15 two openings are in registry. The forward end 29 of the spring rests against the wall of the drawer and limits the outward movement of the spring. It will now be seen that as the drawer is drawn outward the spring, 20 at first, while the guide presents no great resistance, draws the latter outward with the drawer but when the slide reaches the end of its movement then the further movement of the drawer overcomes the resilience 25 of the spring and permits the drawer to be further drawn out while the slide remains stationary. Thus when the drawer is drawn outward both of the intermediate slides accompany it until arrested by the stops referred to above, when the further movement 30 of the drawer is in relation to the slides.

In order that the drawer may not be carelessly withdrawn completely from the casing, I provide it at its rear end with a stop 30 which engages the lower edge 31 of the front opening when the drawer is fully extended. In order, however, that the stop shall not absolutely prevent the withdrawal of the drawer when it is desired to remove it 40 from the cabinet, the stop is mounted to slide vertically in a guide 31, but frictionally held in adjustable position. At the rear end of the case and in position to engage the upper end of the movable stop 30, I attach a cam 45 32 as shown in Fig. 1. When the drawer is thrust inward, if the stop 30 happens to be in any but its lowermost position, it engages the cam and in its further movement is driven downward into the position in which 50 it engages the lower edge or lip of the front opening when the drawer is again drawn outward. If, however, it is desired to remove the drawer completely from the cabinet it may be drawn outward and the fingers 55 inserted to reach the slide 30 and draw it upward so that its lower end 33 no longer engages the edge of the front opening. The drawer is inserted in the case with the slide in this non-engaging position but when 60 the drawer is fully closed or substantially so the cam 32 again returns the stop to its operative position as before explained.

In order to avoid unnecessary noise and shock and prevent marring furniture on 65 which it may be placed, the drawer is pro-

vided with felt strips 34, 35 which are attached beneath the same at its front and rear edges respectively.

In case the drawer is to be used for containing cards and locking them therein, the 70 front panel of the drawer is formed with a perforation 36 through which a locking rod 37 is inserted, the rod being provided with a knob 38 screwed thereto and having a neck 39 which is grooved at 40 for a purpose 75 which will presently appear. The inner face of the front wall is provided with a slightly bulging liner 41 between which and the front wall is arranged a sheet metal guide 42 for a locking tongue 43. Said tongue slides vertically in the guide and at its lower end is notched to embrace the neck of the rod and enter the groove 39 therein. The rod is thus normally held in position but if desired it may be removed by opening 80 the drawer slightly and lifting the locking slide 43, the upper end of which is slightly turned over to facilitate this operation. Guide 42 is further formed with tongues 85 44 which engage perforations in the liner 90 and have the purpose of holding the latter in position.

I claim:

1. In a device of the class described, a casing having an opening therein, a drawer arranged to enter said opening and be received in the casing, guides in the casing, intermediate slides received in said guides, means to limit the movement of said slides, drawer slides mounted on the drawer and engaging said intermediate slides, there being openings in the sides of the drawer and slides respectively adapted to register when the drawer is in its innermost position and leaf springs mounted within the drawer having curved offset portions adapted to enter said openings and yieldingly engage the intermediate slides. 95

2. In a device of the class described, a casing having an opening therein, a drawer adapted to enter said opening, a stop slidably mounted for reciprocation transversely of the drawer at its rear end and adapted to be projected to engage the casing to prevent accidental withdrawal of the drawer therefrom and a cam mounted in the casing to engage and project said stop when the drawer is moved inwardly in the casing. 110

3. In a device of the class described, a casing having an opening to receive a drawer and a stop adjacent the opening, a drawer mounted in the casing and extending into said opening, a vertically-reciprocable slide mounted in the rear end of said drawer and adapted when in one position to engage said stop on the casing and when in the other position to pass by said stop and a cam mounted in the casing to engage said slide when the drawer is inserted and move said slide into position to engage said stop. 120 125 130

4. In a device of the class described, a casing having an opening therein to receive a drawer, a stop, a drawer adapted to enter said opening in the casing, a slide mounted on the rear wall of said drawer, a guide upon said wall in which the slide is vertically reciprocable into and out of stop-engaging position and a cam in said casing adapted to actuate said slide.
5. In a device of the class described, a casing, a drawer adapted to be received in said casing, a stop on one of said elements and mounted for movement transverse to the direction of movement of the drawer, a stop on the other of said elements adapted to be engaged thereby and a cam adapted to engage the movable stop if the latter is in inoperative position when the drawer is slid into the casing.
6. In a device of the class described, a casing having an opening therein, a drawer arranged to enter said opening and be received in the casing, a side wall of said drawer being formed with a lateral recess, guides in the casing, intermediate slides received in said guides, means to limit the movement of said slides, drawer slides mounted on the drawer and engaging said intermediate slides, there being openings in the intermediate slides and the recess-bounding portion of the drawer wall, said openings adapted to register when the drawer is in its innermost position, and a leaf-spring mounted in the recess in the drawer wall and having an offset latch-portion adapted to enter said openings and yieldingly engage said intermediate slides.
7. In a device of the class described, a casing having an opening therein, a drawer arranged to enter said opening and be received in the casing, said drawer having side walls of sheet metal struck up intermediate their upper and lower edges to form outwardly extending ribs, drawer slides mounted on said ribs, intermediate slides engaged by said drawer slides, said intermediate slides, drawer slides and rib walls being provided with openings registering when the drawer is in its innermost position, leaf-springs having offset latch-portions adapted to enter said opening and yieldingly engage the intermediate slides, said leaf-springs mounted in the recesses formed within said ribs, guides in the casing engaged by said intermediate slides, and means to limit the movement of said intermediate slides relative to said guides.
